BLOWPIPE

Wilgot J. Jacobsson, Plainfield, N. J., assignor to
 Union Carbide and Carbon Corporation, a corporation of New York

Application September 15, 1944, Serial No. 554,190

7 Claims. (CL. 158—27.4)

1

This invention relates to blowpipes, and more particularly to blowpipes including an elongated mixer or injector nozzle for one gas, the front end of which nozzle is critically spaced from the rear end of a mixer tube to provide an annular inlet for another gas.

In such blowpipes the elongated or extended mixer nozzle is subject to undesirable axial expansion due to heating, especially that caused by popping or backfiring, which causes a reduction in the annular gas inlet space, with a corresponding decrease in the gas flowing through such space to the mixing chamber. This reduction in some cases even goes so far as to completely close such space, causing one gas to be entirely shut off, and rendering the blowpipe inoperative.

The main object of this invention is to overcome such trouble by the provision of novel gas-tight bearing means for the rear end portion of the mixer nozzle, and resilient means urging such nozzle forwardly, so that the nozzle is free to expand or contract longitudinally without changing the critical gas inlet space at the front end thereof. Another object of the invention is to provide an improved blowpipe in which a combustible gas and a combustion-supporting gas are efficiently and effectively mixed regardless of changes in the length of cooperating mixer parts with respect to one another due to expansion or contraction.

In accordance with the invention, there is provided an elongated mixer nozzle with front end lugs which are adapted to engage and space the nozzle from the annular surface at the rear end of a mixer tube to provide an inlet for one of the gases, such lugs being held in constant contact with such surface by a spring, the force of which is transmitted through the nozzle. A gas-tight seal is provided at the rear end of the mixer nozzle. Such seal includes a spring loaded plastic bearing so that the nozzle is free to expand and contract longitudinally without affecting the critical gas inlet space at the front end of the nozzle.

Referring to the drawing:

Fig. 1 is a fragmentary view partly in side elevation and partly in longitudinal cross-section of a deseaming blowpipe exemplifying the invention, and

Fig. 2 is an enlarged fragmentary sectional view taken on line 2—2 of Fig. 1.

The blowpipe B includes a valve body 10, a tubular shell 12, a head and a nozzle, the latter two elements being omitted from the drawing. The valve body 10 is provided with an inlet 14 for

2

one gas, in this case oxygen, and a separate inlet 16 for another gas, in this case acetylene. The gas inlets 14 and 16 are connected to suitable sources of oxygen and acetylene by conventional means including hose nipples 18 and 20 which are threaded into the inlets 14 and 16, respectively.

The valve body 10 is also provided with a socket 22 in which is threaded a plug 24 containing a cutting or deseaming oxygen valve having a stem 26 which is connected to one end of an operating lever 28. The lever 28 is pivoted to the valve body 10 at 30 and includes a handle 32 which overlaps the shell 12 so that the shell may be gripped in one hand and the handle 32 operated with the thumb of such hand. When the cutting or deseaming oxygen valve is open, the oxygen inlet 14 is placed in communication with an oxygen passage 34 in the valve body 10, such passage 34 being connected to the blowpipe head and nozzle by means including a cutting oxygen pipe 36, the rear end portion of which extends through the shell B.

The valve body 10 is provided with axially aligned front and rear sockets 38 and 40 which are connected by a hole 41. The rear end portion of a preheating oxygen pipe 42 is secured in the socket 38, the pipe 42 extending through the shell 12 in substantially parallel relation to the cutting oxygen pipe 36. Disposed within the pipe 42 and at a substantial axial distance away from the rear end of such pipe is a preheat-gas mixing tube 44 having a central gas mixing passage or chamber 46. The rear face of the mixing tube 44 constitutes an annular abutment 48 for annularly spaced lugs 50 on the front end of an elongated injector or mixer nozzle 52 which projects centrally into the pipe 42 through the hole 41 of the valve body 10. The elongated nozzle 52 is supported in spaced concentric relation with the pipe 42 by annularly spaced tongues 54 around the forward end portion of the nozzle 52 and by the internal wall of the hole 41 at the rear end portion, the annular surface of the hole 41 providing a bearing for the nozzle as the latter expands or contracts axially.

An elongated annular passage 55 is thus provided between pipe 42 and the nozzle 52 for one of the gases, in this case oxygen, the latter being conducted to the passage 55 from the inlet 14 through a suitable cross passage (not shown) in the valve body 10. Thus, preheating oxygen flows through the annular passage 55 and between the ribs 54 to critical gas inlet space 56 between the front end of the nozzle 52 and the annular abut-

ment 48 at the rear end of the mixing tube 44. At its forward end the nozzle 52 is provided with an insert 58 which is adapted to discharge the acetylene in a fine stream axially into the gas mixing passage or chamber 46. At the same time preheating oxygen flows inwardly toward the acetylene stream through the critical annular space 56.

The rear socket 40 in the gas inlet body 10 is threaded to receive a screw 60 of a closure 62. Seated on the inner end of the screw 60 is a disk 64 having a central stud 66 for internally supporting one end of a compression spring 68, the inner end of which engages the rear end of the elongated nozzle 52. The latter is internally threaded at 69 to be engaged by a removing screw (not shown). The spring 68 urges the nozzle 52 axially forwardly so that the lugs 50 are in constant contact with the abutment 48. Gas leakage between the passage 55 and the socket 40, which is connected to the acetylene inlet 16 by a cross passage (not shown) in the valve body 10, is prevented by a spring loaded packing assembly, including a metal washer 70 seated in the bottom of socket 40, a pair of plastic rings 72, a metal sleeve 74, and a compression spring 76 which is disposed between the metal sleeve and the disk 64, around the compression spring 68. The force of the spring 76 is transmitted to the plastic packing ring 72 through the sleeve 74 so that longitudinal floating of the rear end portion of the elongated nozzle 52 is possible without affecting the gas-tight seal between the nozzle and the valve body 10.

The valve body 10 may be provided with conventional valves (not shown) for controlling the flow of oxygen and acetylene to the annular passage 55 between the pipes 42 and 52, and to the socket 40, respectively.

The blowpipe B is operated in a conventional manner when connected to suitable sources of oxygen and acetylene, the preheating gas mixture being delivered to the nozzle from the mixing chamber 46, and the supply of cutting or deseam-ing oxygen being controlled by manipulating the handle 32 in the usual operation of the blowpipe. However, backfire or popping which causes the elongated nozzle 52 to increase in length due to expansion, does not affect the critical clearance between the front of the nozzle and the corresponding annular surface of the abutment 50, because the rear end portion of the nozzle 52 is free to float or move with respect to the valve body 10, the compression springs 68 and 76 maintaining the parts in proper position.

While the invention has been exemplified in connection with a "medium-pressure" mixer, i. e., one in which the acetylene or other fuel gas is axially discharged into the center of the mixing chamber and the combustion supporting gas is annularly discharged inwardly toward the fuel gas, the invention is equally applicable to "low-pressure" mixers, i. e., those in which the combustion supporting gas is axially discharged into the center of the mixing chamber and the acetylene or other fuel gas is annularly discharged inwardly toward the combustion supporting gas as it enters the mixing chamber. The invention is also applicable to "high-pressure" mixers.

I claim:

1. A blowpipe comprising, in combination, an elongated pipe containing a gas mixing tube, an elongated mixer nozzle subject to undesirable longitudinal expansion and contraction due to temperature changes and disposed in spaced con-

centric relation within said pipe to provide an annular passage therebetween, said nozzle being adapted to discharge a stream of gas axially into said tube, means disposed adjacent the front end of said nozzle for spacing the front end of said nozzle from the rear end of said mixing tube to provide a gas inlet to said mixing tube, means for supplying one gas to the annular passage between said nozzle and pipe, means for supplying another gas to said nozzle, gas-tight bearing means disposed between the rear end portions of said pipe and nozzle, the rear end portion of said nozzle being free to expand and contract longitudinally in said gas-tight bearing means, and resilient means urging said nozzle forwardly within said pipe.

2. A blowpipe comprising, in combination, an elongated pipe containing a gas mixer having an annular surface, an elongated mixer nozzle subject to undesirable longitudinal expansion and contraction due to temperature changes and disposed in spaced concentric relation within said pipe for discharging a stream of gas axially into said gas mixer, means disposed adjacent the front end of said nozzle for spacing the front end of said nozzle from the annular surface of said gas mixer to provide a gas inlet space to said mixer, means for supplying combustion-supporting gas to an annular passage between said nozzle and pipe, means for supplying combustible gas to said nozzle, and gas-tight means disposed between the rear end portions of said pipe and nozzle, the rear end portion of said nozzle being free to expand and contract longitudinally in said gas-tight means.

3. A blowpipe comprising, in combination, an elongated pipe containing a mixing tube having an annular rear end, an elongated mixer nozzle subject to undesirable longitudinal expansion and contraction due to temperature changes and disposed in spaced concentric relation within said pipe for discharging a stream of gas axially into said tube, means disposed adjacent the front end of said nozzle for spacing the front end of said nozzle from the rear end of said mixing tube to provide a gas inlet to said mixing tube, means for supplying one gas to the annular space between said nozzle and pipe, means for supplying another gas to said nozzle, gas-tight bearing means disposed between said pipe and nozzle, said nozzle being free to expand and contract longitudinally in said gas-tight means, and spring means urging said nozzle forwardly within said pipe.

4. In a blowpipe, the combination with a valve body having axially aligned front and rear sockets and a connecting hole, a pipe having one end portion secured in said front socket, an annular abutment in said pipe, an elongated mixer nozzle in said pipe, means acting to space the forward end of the nozzle from said abutment, means acting to space said pipe and nozzle so that they are concentric with an annular gas passage therebetween, said hole providing a bearing for the rear end portion of said nozzle, a closure for said rear socket, a compression spring disposed between said closure and the rear end of said nozzle for urging said nozzle forwardly against said abutment, and a spring loaded gas-tight packing in said rear socket for said nozzle.

5. In a blowpipe, the combination with a valve body having axially aligned front and rear sockets and a connecting hole, a pipe having one end portion secured in said front socket, an annular abutment in said pipe, an elongated mixer nozzle in said pipe and having means engaging said

abutment to space the forward end of the nozzle from said abutment, said nozzle also having means engaging said pipe so that the nozzle and pipe are concentric with an annular gas passage therebetween, said hole providing a bearing for the rear end portion of said nozzle, a closure for said rear socket, a disc seated on said closure, said disc having a central stud facing said nozzle, a compression spring disposed between said disc and the rear end of said nozzle for urging said nozzle forwardly against said abutment, the rear end of said spring surrounding said stud, and means providing a gas-tight seal between said valve body and said nozzle.

6. In a blowpipe, the combination with a valve body having axially aligned front and rear sockets and a connecting hole, a pipe having one end portion secured in said front socket, an annular abutment in said pipe, an elongated mixer nozzle in said pipe and having means engaging said abutment to space the forward end of the nozzle from said abutment, said nozzle also having means engaging said pipe so that the nozzle and pipe are concentric with an annular gas passage therebetween, said hole providing a bearing for the rear end portion of said nozzle, a closure threaded in said rear socket, a disc seated on said closure, said disc having a central stud facing said nozzle, a compression spring disposed between said disc and the rear end of said nozzle for urging said nozzle forwardly, the rear end of said spring surrounding said stud, and a gas-tight packing in said rear socket for said nozzle, said packing comprising a metal washer surrounding said nozzle in the bottom of such socket, a pair of plastic packing rings between said nozzle and the inner wall of the socket, a metal sleeve adjacent the rear end of the nozzle, and a compression spring disposed between said sleeve and said disc and surrounding said first-named spring.

7. In a blowpipe, a body having a socket provided with a gas inlet and a smooth hole of reduced diameter disposed in front of said socket, a tubular gas conducting member slidably supported in said hole and having one end thereof projecting rearwardly into said socket, an adjustable closure for said socket, a disc seated on said closure, said disc having a central stud facing said tubular member, a compression spring disposed between said disc and the inner end of said tubular member, urging said tubular member forwardly in position, the rear end of said spring surrounding said stud, and a gas-tight packing in said socket for said tubular member comprising a washer surrounding said tubular member in said socket, a packing ring between said tubular member and the inner wall of the socket, a sleeve on the rear end of the tubular member, and a compression spring disposed between said sleeve and said disc and surrounding said first-named spring.
